UNITED STATES PATENT OFFICE.

CHARLES A. STUART, OF KENOSHA, WISCONSIN, ASSIGNOR TO SIMMONS COMPANY, OF KENOSHA, WISCONSIN, A CORPORATION OF DELAWARE.

DESIGN FOR A BEDSTEAD FRAME.

Application filed September 21, 1922. Serial No. 3,780. Term of patent 14 years.

To all whom it may concern:

Be it known that I, CHARLES A. STUART, a citizen of the United States, residing at Kenosha, in the county of Kenosha and State of Wisconsin, have invented a new, original, and ornamental Design for Bedstead Frame, of which the following is a specification, reference being had to the ac-

companying drawing, forming a part thereof.

The drawing is a perspective view of a bedstead frame showing my new design.

I claim:

The ornamental design for a bedstead frame, as shown.

CHARLES A. STUART.
